UNITED STATES PATENT OFFICE.

JULIUS H. RICHARDS, OF NEWARK, NEW JERSEY, ASSIGNOR TO SPLITDORF ELECTRICAL COMPANY, OF NEWARK, NEW JERSEY.

SWITCH MECHANISM.

1,325,654.

Specification of Letters Patent. Patented Dec. 23, 1919.

Application filed December 2, 1916. Serial No. 134,750.

To all whom it may concern:

Be it known that I, JULIUS H. RICHARDS, a citizen of the United States, residing at Newark, in the county of Essex and State

5 of New Jersey, have invented certain new and useful Improvements in Switch Mechanism, of which the following is a specification.

Generally speaking this invention relates 10 to means for controlling the source of power for dynamo electric machines, which machines may be adapted for a variety of functions, and with which said switching device is designed to coöperate to the attainment 15 of the purposes desired. In particular the present invention contemplates a switch device involving such features of construction and operation as to render it especially applicable to the control of dynamo motors of the class known as starting motors, whose duty it is to furnish the necessary power for the starting of prime movers, as for instance the internal combustion engine of automobiles and similar 20 autovehicles:

In my patents for engine starters # 1,254,851 and 1,227,003, patented January 29, 1918, and May 22, 1917, respectively there are shown two types of switches used 25 in conjunction with starting motors and whose operation are well described therein. It is then one of the objects of my present invention to provide a switching mechanism of the class shown in said applications 30 but involving several improvements in construction and arrangement of parts to be hereinafter described; and it further aims, when used in connection with starting motors, to fulfil the wide range of requirements 35 which a device of this character is called upon to meet owing to the various types of starting systems now used for automobile engines.

Another object is to design the several 40 members such that they may be conveniently and compactly arranged in a switch housing whereby the whole mechanism may be attached as a single structure in some suitable location relative to the motor with 45 which it is adapted to coöperate.

These and other objects will be readily understood by those skilled in the art from

a consideration of the following description, taken together with the accompanying drawings which constitute a part of this 55 specification.

In the drawings, Figure 1 is a top plan view with certain parts shown in section, and with the cover removed to illustrate the interior construction of my switch, and also 60 showing certain external devices coöperating with the switch proper to perform whatever other function for which it is suitably adapted.

Fig. 2 is a side elevation of Fig. 1, partly 65 in section, and with a portion of the housing structure broken away, and further showing in dotted lines an electric motor, whose circuits are to be controlled by the switch. There is also seen in this view the 70 manner in which the forces applied for the purpose of actuating the switch may be transmitted through the agency of other switch members and be brought into play to move certain parts of the motor itself. 75

Fig. 3 is a view, similar in nature to Fig. 1 on a somewhat larger scale, and showing a slight modification of the invention, with certain parts removed.

Fig. 4 is a diagrammatic showing of the 80 circuit connections involved when my switch is applied as a means for controlling electric motors.

With particular reference to the drawings wherein like reference symbols designate 85 like parts throughout, 1 is a unitary structure which serves the dual purpose of housing and supporting the switching mechanism. This housing is mounted in its working position as a single structure and hence 90 it will be obvious that it may be altered in size and contour to suitably adapt it to the numerous systems to which this switch is capable of application. Inasmuch as my invention is especially suited to the control of 95 starting motors, I have shown one method of mounting the housing 1 directly upon the motor frame, being held in place by screws 2. Secured on the inner opposite sides of housing 1 as by bolts 3 and 4 are two switch blades 5 and 6. The assembly of blade 6 is 100 preferably accomplished by an oblong hole therein through which bolt 4 passes. This provision permits adjustment of said blade

in order to vary the time at which the same is contacted by its corresponding switch runner, hereinafter to be referred to. These blades are properly insulated in a well known manner by bushing and insulators 50—51 from housing 1 and comprise a plurality of strips of resilient metal such as spring copper. Their resiliency may further be increased if desirable by making one of said strips of steel, (preferably the outer one) while to increase flexibility said blades are, for a portion of their lengths, slotted so that each blade consists of several sections as seen in Fig. 2. Switch blade 5 is seen to be somewhat longer than blade 6, the reason for which will later be explained. Parallelly supported by and adapted to slidably extend through the switch housing 1 are two rods 7 and 8, hereinafter to be termed as the switch rod and pull rod respectively. Within the housing there are two collars 9 and 10 mounted securely upon the rods 7 and 8, and which are adapted to rest adjacent the end wall of said housing when these rods are in their normal position. A very unique method has been employed for securing these collars in place upon their respective rods, which I will now describe. In the end of each collar is a slight counterbore the walls of which are in the nature of a circular groove and the arc of which groove is substantially a semi-circle. At points in each rod adjacent the grooves in these collars there is provided a corresponding circular groove. Coöperating with the grooves in the sleeve and rod in each case is a resilient circular ring. Said rings are suitably made of circular stock and are of such diameter and resiliency as to engage both rod and collar to thereby fasten the respective collars firmly in place, yet should it be necessary, the said collars 9 and 10 may readily be removed. The above mentioned rings are shown respectively at 11 and 12. Mounted upon rods 7 and 8 adjacent collars 9 and 10 are shouldered insulating rings 13 and 14 respectively. Supported upon the shoulders of said rings are switch runners 15 and 16. These runners are of suitable conducting material as of copper, and are of U-shaped construction, the arms of which are adapted to slidably coöperate with each other and with switch blades 5 and 6 to complete the electrical circuit between bolts 3 and 4. Runner 15 is provided with longer working surfaces than those of runner 16 for a purpose to be described hereinafter. Adjacent the runners 15 and 16 for the purpose of holding the same in place are insulating washers 17 and 18. Said washers are pressed against their respective runners by means of compression springs 19 and 20, which springs have their other ends confined by collars 21 and 22 respectively. A means

similar to that described in connection with collars 9 and 10 is used to secure said collars 21 and 22 upon the rods 7 and 8. In order to allow said switch runners considerable freedom of movement upon the rods 7 and 8 I have provided a clearance between the insulating rings 13 and 14 and their respective rods 7 and 8. The advantage of this feature resides in the fact that as said rods are operated to and fro said switch runners are permitted to line themselves up properly and to equalize the lateral pressure they receive by their pressing engagement with blades 5 and 6. In this way said runners bear upon each other evenly and coöperate with their respective switch blades without the liability of any binding or other undesirable results. Disposed about both the switch rod and pull rod are resilient members 23 and 24. These members are designed as compression springs, being adapted to occupy the space between the collars 21 and 22 respectively and the end of the switch housing. It is the function of these springs to exert their pressure upon the collars 21 and 22 and thereby tend to constantly maintain rods 7 and 8 in their normal positions as shown in the figures. Suitable covers 45 and 46 are attached to the housing 1 as by screws 47 to provide a protecting inclosure for the working elements of the switch mechanism.

In Fig. 3, 1^a is a switch housing fastened directly upon the motor frame by screws 2^a. Secured on the inner opposite sides of housing 1^a as by bolts 3^a and 4^a are two switch blades 5^a and 6^a. The assembly of one of the blades, such as 6^a is preferably accomplished by an oblong hole therein through which bolt 4^a passes. This provision permits adjustment in said blade in order to vary the time at which the same is contacted by its coöperating switch runner, hereinafter referred to. These blades are properly insulated in a well known manner by bushings and insulators 50^a and 51^a from housing 1^a and are preferably made up of a plurality of strips of resilient metal such as spring copper. Their resiliency may further be increased if desired by making one of said strips out of steel, preferably the outer one, while to increase the flexibility said blades are, for a portion of their length, slotted so that each blade consists of several sections as seen in Fig. 2. Parallelly supported by and adapted to slidably extend through the switch housing 1^a are two rods 7^a and 8^a, hereinafter to be termed as the switch rod and pull rod respectively. Within the housing there are two collars 9^a and 10^a mounted securely upon the rods 7^a and 8^a, and which are adapted to rest adjacent the end wall of said housing when these rods are in their normal position. Similar methods of fas-

tening these collars on their respective rods by rings 11^a and 12^a are used as described in connection with Fig. 1. Mounted upon the rods 7^a and 8^a adjacent to the collars 9^a and 10^a are shouldered insulating rings 13^a and 14^a respectively. Supported upon the shoulders of said rings are switch runners 15^a and 16^a. These runners are of suitable conducting material as of copper, and are of U-shaped construction, the arms of which are adapted to slidingly coöperate with each other and with switch blades 5^a and 6^a to complete the electrical circuit through the bolts 3^a and 4^a. Runner 15^a is provided with longer working surfaces than those of runner 16^a for similar purposes to be described in connection with runners 15 and 16 in Fig. 1. Adjacent the runners 15^a and 16^a for the purpose of holding the same in place are insulating washers 17^a and 18^a. Said washers are pressed against their respective runners by means of compression springs 19^a and 20^a, which springs have their other ends confined by collars 21^a and 22^a respectively. Means similar to that described in connection with collars 9^a and 10^a is used to secure said collars 21^a and 22^a to the rods 7^a and 8^a. In order to allow said switch runners considerable freedom of movement upon the rods 7^a and 8^a, I have provided a clearance between the insulating rings 13^a and 14^a and their respective rods 7^a and 8^a. The advantage of this construction is the same as that pointed out in connection with the construction of Fig. 1. Disposed about the switch rod and pull rod are resilient members 23^a and 24^a which perform the same function as springs 23 and 24 in connection with Fig. 1. The parts 25^a, 32^a and 35^a correspond to similar parts 25, 32 and 35 in Fig. 1 and no further description is necessary.

Considering now the remaining portion of my switch mechanism, and in particular the portion disposed exterior of the housing wherein the switch proper is contained, it will be seen that the housing structure 1 also carries two rods 25 and 26. Said housing is provided with two circular recesses into which the rods 25 and 26 are adapted to be forced to secure the same rigidly in place substantially parallel to the above mentioned rods 7 and 8. Slidably mounted upon rods 25 and 26 and guided thereby is a member 27, which for obvious reasons is suitably termed a force transmitting member. Said member is securely attached to switch rod 7 as by nuts 28 and is also provided with a depending portion 29. Carried by guide rods 25 and 26 and fastened thereto by set screws 30 is a brace 31, which guidingly supports the pull rod 8 in its longitudinal movement. At the other end of said pull rod is a connecting link 32 adapted to be connected

to any suitable system of levers whereby said rod receives its operating force. Also carried by rod 8 is a device generally indicated at 33 which is adapted to coöperate with a pawl 34 on member 27 in such a way that a pull applied to link 32 to move rod 8 longitudinally is transmitted by the force transmitting member 27 to switch rod 7, whereby said switch rod and member 27 are moved forward with pull rod 8. I will not attempt to give a detail description of the device 33 as this has been fully described in the above-mentioned patent #1,254,851 issued January 29, 1918. Suffice it to say that in the operation just described, should for any reason the motion of member 29 be obstructed before runners 15 and 16 had completed the circuit between blades 5 and 6, said device 33 becomes effective to permit pull rod 8 carrying a collar 48 held in working position on rod 8 by snap ring 49 and which collar is slidable in barrel 33, to continue in its movement independently of switch rod 7 to carry switch runner 16 forward and finally complete the circuit between said blades. And furthermore it will be obvious that the results obtained by thus closing the switch may be made instrumental in removing said obstruction to thereby restore device 33 to its normal condition.

Describing the operation of my switch, let it be assumed that this switch is to be used in connection with a starting motor as seen in Figs. 1 and 2. All parts are in their normal position, the blade 5 being sufficiently long to permanently contact runner 15 to 100 guidingly hold both runners 15 and 16 in proper working relationship. If a force is now applied to rod 8 said rod is moved longitudinally, and through the coöperation of members 27 and 33 rod 7 is likewise moved until switch runners 15 and 16 have assumed the position shown in dotted lines, Figs. 1 and 3, to close the electric circuit through the motor M and battery B. At the same time the portion 29 of the force transmitting member is also moved longitudinally, and which motion may be adapted to connect the motor to the engine to be started. Just previous to the time runners 15 and 16 have acquired the position shown in dotted lines, pawl 34 engages the head of a bolt 35 which effects an unlocking of the rods 7 and 8 and thereby places rod 7 in condition to be returned due to the starting of the engine. Likewise said unlocking operation also renders pull rod 8 independent of rod 7 and when released will return to its normal position under the force of spring 24. It was noted above that runner 15 was somewhat longer than runner 16. The reason for this is, that should switch rod 7 be arrested in its movement as by an obstruction to the motion of the force transmitting member 27, above

described, the arms of runner 15 will be sufficiently long to maintain contact with runner 16 while the latter is moving forward to engage switch blade 6 to thereby complete the circuit through the motor. A feature of the automatic locking connection between rods 7 and 8 resides in the fact that the time at which such connection is released may be varied at will. This is accomplished by 10 either raising or lowering the adjustable bolt 35, the same being conveniently mounted on the housing structure 1.

While my present invention is in nature similar to the switching device shown in my 15 previous patents hereinbefore mentioned, yet it will be apparent from the foregoing that it involves several useful and desirable improvements both in construction and efficiency of operation. Among these is the 20 feature of providing a clearance between rods 7 and 8 and the insulating rings 13 and 14, which support switch runners 15 and 16 respectively. In this way said runners keep themselves properly aligned at all times. Another feature is the use of springs 19 and 20 which, in contradistinction to the devices shown in the above said applications, maintain a constant pressure upon runners 15 and 16 for all positions of rods 7 and 8. By the 25 use of these springs I am enabled to space the collars 21 and 22 from the switch runners sufficiently to avoid any danger of interference therewith, while at the same time the process of assembling is very much simplified.

Another feature of my switch, as shown in Fig. 1, resides in the fact that, while being operated to close or open the circuit, but one contact is actually made or broken. By such 40 a provision the arcing of contacts is greatly reduced, an important item where heavy currents are involved.

It is to be understood that the language of this specification is merely descriptive of 45 my invention. I am well aware that many changes and alterations may be made in the embodiments shown without departing from the spirit of said invention and the scope of the appended claims, and I therefore do not 50 care to be limited to the exact details shown and described.

Having thus described my invention what I claim is:—

1. A switch mechanism having in combination, a unitary housing member, switch blades adjustably mounted within the said housing on opposite sides thereof, a pair of rods extending through said housing, switch runners acted on by said rod and adapted 55 to be moved in circuit closing relation with said switch blades, means serving to hold said switch runners in their normal open-circuit position, a force transmitting member secured to one of said rods, locking

means between said member and the other 65 of said rods whereby when a pull is applied to the last mentioned rod the force transmitting member together with the rod to which it is secured are moved to carry said switch runners into circuit closing relation 70 with the switch blades, and means to release said locking means after said circuit has been closed to thereby place the first mentioned rod in condition to return to its normal position independent of the other of 75 said rods.

2. A switch mechanism having in combination, a unitary housing structure, a pair of rods extending through said housing, switch 80 blades within said housing, switch runners actuated by said rods and adapted to be moved into circuit closing relation with said switch blades, means serving to hold said switch runners in their normal open circuit position, a force transmitting member 85 secured to one of said rods, locking means between said member and the other of said rods, whereby when a pull is applied to the last mentioned rod the force transmitting member together with the rod to which it 90 is secured are moved to carry said switch runners into said circuit closing relation with the switch blades, and means associated with the housing structure to release said locking means after said circuit has been 95 closed to thereby place the first mentioned rod in condition to be returned to its normal position independently of the other of said rods.

3. A switch mechanism having in combination, a unitary housing structure, a switch rod and a pull rod supported thereby and extending therethrough, switch blades within said housing but insulated therefrom, switch runners mounted upon said rods 105 adapted to coöperate with each other and with said switch blades to give an electrical connection between said blades when said rods are operated, means carried by these rods serving to hold the same in their inoperative position, a force transmitting member secured to move with said switch rod exterior of the housing, a compensating device carried upon said pull rod and means for locking a part of the compensating device to said force transmitting member, whereby when a pull is exerted upon the pull rod said switch rod is moved therewith, said compensating device serving also to permit the switch runners to pass into circuit closing relation with said switch blades should said force transmitting member have its movement obstructed.

4. A switch mechanism having in combination, a unitary housing structure, switch blades therewithin, a switch rod and a pull rod supported by said structure and extending therethrough, switch runners within

- said housing adapted to be actuated by said rods to provide an electrical connection between said blades, a force transmitting member secured to the switch rod for movement therewith, a pawl carried by said member, means on the pull rod coacting with said pawl to lock said rods together, whereby when a pull is exerted upon said pull rod said switch rod is actuated therewith to move said runners into electrical connection with the switch blades, and means on said housing structure coacting with said pawl to unlock said rods after said electrical connection has been made to thereby render either of said rods independent of the other.
5. A switch mechanism having in combination, a unitary housing structure, switch blades within said housing, a pull rod and a switch rod supported by said housing and extending therethrough, runners mounted upon said rods and movable therewith, flexible means to hold said runners in place upon said rods, means for applying a force to said pull rod, a locking device between said rods exterior of said housing such that when a pull is exerted upon said pull rod both rods are moved together to carry said runners into electrical contact with said switch blades, and means coacting with said locking device for releasing the same after said electrical contact has been made, said last means being adjustable to vary the time at which said locking device is released.
6. A switch mechanism having in combination, a unitary housing structure, a plurality of switch blades within said housing and supported thereby, a plurality of movable rods extending through and supported by said housing, a plurality of switch runners within said housing and controlled by said rods, means exterior of said housing coöperating between said rods whereby the same are adapted to move together when a force is applied to one of them to carry said switch runners into circuit making relationship with said switch blades, said coöperating means further serving to render said rods independent of each other after said runners have been moved into such circuit relationship with said switch blades.
7. A switch mechanism having in combination, a unitary housing and supporting structure, switch blades supported within said housing, a switch rod and a pull rod slidably extending through said housing, switch runners actuated by said rods to contact with said blades, guiding members carried by said housing structure, a force transmitting member slidably mounted upon said members and secured to the switch rod, means on the pull rod coacting with said force transmitting member whereby when a pull is exerted upon the pull rod said switch rod is moved therewith to carry said runners into contact with said switch blades, said means serving also to permit the pull rod to advance independently of said switch rod should said force transmitting member have its movement obstructed.
8. A switch mechanism having in combination, a housing, stationary switch members therein, movable switch members adapted to coöperate with said stationary members, members for actuating said movable switch members, and automatic means coöperating between said actuating members whereby said actuating members may be initially moved together and independently after the initial movement is completed.
9. A switch mechanism having in combination, a housing, stationary switch members therein, movable switch members adapted to be moved to make contact with said stationary members, means for manually actuating said movable members to make such contact, and automatic means coöperating between said manual means whereby the manually operated means may be initially moved as a whole and subsequently in part.
10. A switch mechanism having in combination, a housing, stationary switch members therein, movable switch members adapted to be moved into circuit relation with said stationary members, members for manually moving said movable members into said circuit relation with the stationary members, automatic means coöperating between said manually movable members whereby said manually moving members, may be initially moved together and independently thereafter, and automatic means to move said movable members out of circuit relation with the stationary members.
11. A switch mechanism having in combination, a housing structure, stationary switch members therein, movable switch members therein and adapted to coöperate with said stationary members, members for actuating said movable switch members, and automatic means coöperating between said actuating members whereby said actuating members may be initially moved together and independently thereafter for the purpose of carrying said movable switch members into circuit making relation with said stationary switch members.
12. A switch mechanism having in combination, a housing structure, stationary switch members therein, movable switch members therein and adapted to coöperate with said stationary members, members for actuating said movable members, automatic means coöperating with said actuating members whereby said actuating members may be initially moved together and independently thereafter for the purpose of carrying said movable switch members into circuit making relation with said stationary mem-

bers, and means attached to said housing structure for inclosing all of said parts.

13. A switch mechanism having in combination, a housing structure, stationary switch members therein, movable switch members therein and adapted to coöperate with said stationary members, members for actuating said movable members, automatic means coöoperating with said actuating members whereby said actuating members may be initially moved together and independently thereafter for the purpose of carrying said movable switch members into circuit making relation with said stationary members, automatic means serving to break said circuit relation, and means associated with said housing structure for inclosing all of said parts.

14. A switch mechanism having in combination, a housing, a pair of switch blades therein, a pair of movable switch members within said housing, members passing through but flexibly attached to said movable switch members for actuating said movable members, said pair of movable members coöoperating with each other and said blades in such a way when operated that the lateral pressure from said blades on the movable switch members are equalized as and for the purpose described.

15. A switch mechanism having in combination, a housing, adjustable switch blades mounted therein, a pair of manually actuated members located in the housing between said switch blades, a switch member flexibly carried upon each of said manually actuated members and in constant electrical contact with each other and adapted to establish an electrical connection between said switch blades in the manner described when the manually actuated members are operated as described.

16. A switch mechanism having in combination, a housing structure, a pair of switch blades within said housing, a pair of rods extending through said housing, a pair of switch runners actuated by said rods and adapted to slidingly and yieldingly coöperate with said blades and also with each other, said runners being loosely mounted upon said rods so that the pressure received from said blades is shared by both runners, and resilient means exerting a constant force upon said runners to hold the same in position upon said rods at all times.

17. A switch mechanism having in combination, a housing structure, a pair of flexible switch blades therewithin, a pair of parallel rods projecting through said housing, a pair of switch runners one on each of said rods in permanent contact with each other and adapted to be actuated by said rods to make contact with said flexible switch blades, said runners being loosely mounted upon

said rods so that the pressure received from 65 blades is shared by each runner and further to permit said runners to keep themselves properly aligned, a collar upon each rod, and a constant pressure spring upon each rod for holding said runners in place adjacent said 70 collars.

18. A switch mechanism having in combination, a unitary housing structure, switch blades therewithin, a pair of rods extending therethrough, a switch runner on each rod 75 and actuated thereby in such a way that one runner contacts with one of said blades and the other runner with the other of said blades to give an electrical connection between said blades, said runners being in permanent contact with each other and means whereby one of said runners may be moved slidingly with respect to but independently of the other of said runners to complete said electrical connection should said last mentioned runner have its motion obstructed.

19. A switch mechanism having in combination, a housing, a pair of actuating rods extending therethrough, switch blades mounted with said housing and on opposite 90 sides thereof with their working surfaces substantially parallel to said rods, switch runners mounted upon said rods in such a manner as to have lateral movement thereon and in constant electrical engagement 95 with each other and held in place by spiral springs, said runners being adapted to establish an electrical connection between said blades when actuated by said rods in such a manner as to equalize the lateral pressure 100 of said blades on said runners.

20. A switch mechanism having in combination, a housing, a pair of actuating members extending therethrough, switch blades mounted within said housing on opposite 105 sides of said actuating members, U-shaped switch runners loosely mounted upon said members and in constant electrical engagement with each other, and resilient means to hold the runners in place on said members, said runners being adapted to establish an electrical connection between said blades when moved by said actuating members, resilient means tending to hold said runners in open circuit position relative to said switch 115 blades, said switch blades being adjustable whereby the time of engagement of the runners therewith may be varied.

21. A switch mechanism having in combination, a unitary housing and supporting 120 structure, a pair of switch blades mounted within said housing, a pair of rods supported by and extending through said housing structure, a collar fixed upon each rod, supporting insulating members loosely mounted on said 125 rods adjacent said collars, switch runners supported by said members, insulating washers adjacent said switch runners, a second collar

fixed upon each rod and compression springs between said second collars and said washers whereby said runners are yieldingly held in place, means whereby when one of said 5 rods is actuated said other rod is moved therewith to carry said runners into contact making relation with said switch blades, said loosely mounted insulating members per-

mitting said runners to keep themselves alined at all times, and a second spring on each rod disposed between said second collars and the end of said housing and serving to hold said runners in their normal open circuit position.

In witness whereof I affix my signature,
JULIUS H. RICHARDS.
